ATTORNEY.

UNITED STATES PATENT OFFICE.

FREDERICK GUNNARSON, OF OGDEN, UTAH.

ROLLER-SKATE.

1,327,549.

Specification of Letters Patent.

Patented Jan. 6, 1920.

Application filed March 8, 1919. Serial No. 281,328.

To all whom it may concern:

Be it known that I, FREDERICK GUNNARSON, a citizen of Sweden, residing at Ogden, in the county of Weber and State of Utah, have invented new and useful Improvements in Roller-Skates, of which the following is a specification.

This invention relates to roller skates, particularly to those of the so called bicycle type, that is those having only two wheels, and has for its object the provision of a skate in which the wheel bearings are supported beneath the foot engaging plates by means of springs, the resilience of which will take up the shocks and jars incident to the travel of the skate over a surface, and whereby the maximum degree of comfort will be afforded the user.

An important object is the provision of a skate of this character which will be simple and inexpensive in manufacture, simple and durable in use, and a general improvement in the art.

With the above and other objects and advantages in view, the invention consists in the details of construction to be hereinafter more fully described and claimed, and illustrated in the accompanying drawing, in which—

Figure 1 is a bottom plan view of a skate constructed in accordance with my invention,

Fig. 2 is a side elevation thereof, and

Fig. 3 is a cross sectional view taken 35 through one of the wheels.

Referring more particularly to the drawing, the numerals 5 and 6 designate plates connected by means of the usual bolts 7 extending through elongated slots 8 whereby the length of the skate may be adjusted, the plate 5 having one end enlarged to form a heel engaging portion 9 and the plate 6 having one end enlarged to form a sole engaging portion 10. A suitable upstanding yoke 11 is secured to the heel portion 9 and is provided with suitable straps, not shown, of ordinary construction and arrangement whereby the skate may be partially secured upon the user's foot. The sole engaging portion 10 is provided with the usual sole engaging clamps 12 adjustable by means of the usual form of screw 13. The above described parts are well known in the art and no novelty is claimed for them.

In carrying out my invention I provide upon the under side of the sole engaging

portion 10 of the plate 6 a pair of oppositely bowed substantially V-shaped springs 14 which may be riveted or otherwise suitably secured upon the sole engaging portion 10 and which carry at their free ends bearings 15 arranged in spaced parallel relation. A front wheel 16 is provided which has its axle 17 journaled in the bearings 15. A U-shaped yoke 18 also receives the axle 17 and is disposed horizontally, that is at right angles to the springs 14. The right portion of the yoke 18 has secured thereto, as shown at 19, one end of a resilient strip 20, which extends at an angle toward and which has its other end secured to the under side of the plate 6, as shown at 21.

The structure at the rear wheel is identically the same as the structure at the front wheel except that the resilient strip 22, corresponding to the strip 20 of the front wheel structure, extends in the opposite direction and the yoke 23, corresponding to the yoke 18, is also oppositely disposed.

From the foregoing description and a study of the drawings, it will be seen that as the skate travels over the surface skated upon the springs 14 at the front and rear wheels will take up any shocks and jars incident to the passage of the wheels over any irregularities. The springs 14 in such case permit the wheels to move toward or away from the supporting plates of the skate, as will be obvious and it is apparent that the provision of the resilient strips 20 and 22 serves to afford sufficient rigidity to the wheel supporting structures while permitting the proper flexibility. It will be evident that as a consequence the use of the skates will be very desirable inasmuch as they will afford the maximum degree of comfort to the user.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A skate comprising a foot engaging member, a pair of oppositely bowed substantially V-shaped leaf-springs secured transversely upon the underside of said foot engaging member at the forward and rear ends thereof, the free ends of said springs extending

vertically downwardly and being formed as bearing members, a wheel disposed between each pair of springs and having its axle journally received within said bearings, a horizontally disposed U-shaped yoke straddling each wheel and having its arms disposed inwardly of said bearing members and journally engaging said axle, the yoke at the forward wheel extending rearwardly and

the yoke at the rear wheel extending forwardly, and an inclined resilient strip secured at one end to the bight of each yoke and having its other end secured to said foot engaging member, said resilient strips converging upwardly. 10

15 In testimony whereof I affix my signature.

FREDERICK GUNNARSON.
